(57) **CLAIM**

The ornamental design for a covered container for food, as
shown and described.

DESCRIPTION

FIG. 1 is a top, side and front perspective view of the first
embodiment of a covered container for food showing our new
design;

FIG. 2 is a bottom, side and front perspective view thereof;
FIG. 3 is a front elevation view, the rear elevation being a
mirror image thereof;

FIG. 4 is a left side elevation view, the right side elevation
being a mirror image thereof;

FIG. 5 is a top plan view thereof;

FIG. 6 is a bottom plan view thereof;

FIG. 7 is a cross-sectional view taken along line 7-7 of FIG. 5;

FIG. 8 is a cross-sectional view taken along line 8-8 of FIG. 5;
FIG. 9 is a top, side and front perspective view of the second
embodiment of a covered container for food showing our new
design;

FIG. 10 is a bottom, side and front perspective view thereof;
FIG. 11 is a front elevation view, the rear elevation being a
mirror image thereof;

FIG. 12 is a left side elevation view, the right side elevation
being a mirror image thereof;

FIG. 13 is a top plan view thereof;

FIG. 14 is a bottom plan view thereof;

FIG. 15 is a cross-sectional view taken along line 15-15 of
FIG. 13;

FIG. 16 is a cross-sectional view taken along line 16-16 of
FIG. 13;

FIG. 17 is a top, side and front perspective view of the third
embodiment of a covered container for food showing our new
design;

FIG. 18 is a bottom, side and front perspective view thereof;
FIG. 19 is a front elevation view, the rear elevation being a
mirror image thereof;

FIG. 20 is a left side elevation view, the right side elevation
being a mirror image thereof;

FIG. 21 is a top plan view thereof;

FIG. 22 is a bottom plan view thereof;

FIG. 23 is a cross-sectional view taken along line 23-23 of
FIG. 21; and,

FIG. 24 is a cross-sectional view taken along line 24-24 of
FIG. 21.
